Primary Examiner—Robert M. Spear*Assistant Examiner*—Mary Ann Calabrese(74) *Attorney, Agent, or Firm*—Connolly Bove Lodge & Hutz LLP(57) **CLAIM**

The ornamental design for a mattress topper, as shown and described.

DESCRIPTION

FIG. 1 is a right side elevational view of a mattress topper showing my new design;

FIG. 2 is a top plan view of the mattress topper of FIG. 1; FIG. 3 is a rear elevational view of the mattress topper of FIG. 1;

FIG. 4 is a front elevational view of the mattress topper of FIG. 1;

FIG. 5 is a bottom plan view of the mattress topper of FIG. 1; and,

FIG. 6 is a left side elevational view of the mattress topper of FIG. 1; and

FIG. 7 is an enlarged fragmental perspective view of the left front corner of the mattress topper illustrating the three dimensional depth of the design.
